UNITED STATES PATENT OFFICE

2,137,551

MOTOR

Warren P. Valentine, Philadelphia, Pa., assignor to National Transit Pump & Machine Company, Oil City, Pa., a corporation of Pennsylvania

Application October 21, 1935, Serial No. 45,991

17 Claims. (Cl. 121—115)

The present invention relates to a method and apparatus for securing substantially synchronous step by step operation of preferably duplicate engines, generally analogous to the operations of the engines of a duplex pump.

A purpose of the invention is to provide a novel method and apparatus of the character indicated that will be at once inexpensive and effective and well suited to the needs of manufacture and of service.

A further purpose is to synchronize two engines by control of the exhaust of each by the other.

A further purpose is to use the engines of a pair of the character indicated alternately at corresponding portions of their strokes, each to reversely adjust the exhaust of the other, each adjustment tending to somewhat slow the adjusting engine or/and to accelerate the other engine which, in turn, reacts similarly on the first.

A further purpose is to slow down each engine at the completion of each stroke of its valve mechanism by suitably throttling the engine exhaust.

A further purpose is to use each stroke of valve mechanism of one engine to additionally open the exhaust of another engine to be kept in step with the first.

A further purpose is to provide a complete release of the engines from their mutually reactive control.

Further purposes will appear in the specification and in the claims.

I have elected to illustrate my invention in one only of its many forms, selecting a form however that is at once practical and effective in operation and which well illustrates the principles involved.

Figure 1 is a fragmentary sectional plan, in part diagrammatic, illustrating a pair of engines cooperatively connected for operation in accord with a desirable form of my invention.

Figures 2 and 2a are sectional perspectives of details of Figure 1.

Figures 3, 4, 5 and 6 are sectional views showing different critical positions, of structure corresponding generally with that of Figure 1, but lacking the detail of that view and intended to be chiefly diagrammatic.

Like numerals refer to like parts in all figures. Describing in illustration and not in limitation and referring to the drawings:—

Parts of two engines of the character indicated paired and suitably duplicate except that their corresponding operating parts are not simultaneously in their same positions, are shown in

Figure 1. Their cylinders appear at 10 and 11 mounted upon a suitable base 12.

Steam from a steam supply line 13, (shown diagrammatically) reaches the main valve steam chests 14, 15 through main throttle valves 16, 17 and reaches suitable or usual pilot valve steam chests 18, 19 through valves 20, 21.

The pilot valve pistons are shown at 22, 23, 22', 23', controlling steam inlet and exhaust passages 24, 25, 26, 27 by which steam is conducted to and exhausted from the main valve. In the main valve are pistons 28, 29, 28', 29', by which slide valve 30 or 30' is shifted to control inlet and exhaust to and from the main cylinders through the ports 31, 32, 31', 32' with exhaust through passages 33, 33' controlled by hand-operated valves 34, 34', to a control cylinder 35 in which operates a control valve 36. The control valve 36 is open at one end to the exhaust pipe 37 and may be partly closed at the other end or open but is there attached to a valve stem 38 operating through a suitable stuffing box.

The pilot valves are connected through stems 39, 39' shown as adjustable for length at 40, and intermediate levers 41, 42, with main piston rods 43, 43', of the respective engines, so that each engine as its piston 44 or 45 approaches an end of a stroke effects its own reversal by shifting the corresponding pilot valve, which, in turn, reverses the steam admission and steam exhaust connections at opposite ends of the main valve chests 14 and 15.

As thus far described the operation is in many respects similar to that disclosed in United States Patent 933,952 to Bird, with which construction there are other similarities in the present case along with marked differences.

The levers 41, 42 are pivoted upon or about the axes of pins 46, 46' which are carried by fixed brackets 47 mounted in any suitable way, as by rods 48.

At their outer ends, those farther from the pivots, the lever arms 41 and 42 are forked at 49 to engage at variant lever lengths with rollers 50 and 51 supported from brackets 52 of general crosshead type, which are clamped or otherwise attached to piston rods 43 and 43'. It has not been considered necessary to show any guides for the crosshead, which will be used or not according to the need.

At their inner ends levers 41 and 42 carry rollers 53 and 54 which engage with limiting contacts 55 and 56, movable with pilot valve piston rods 39, 39' so that the pilot valve piston rods are moved forward and backward by engagement 55

of the rollers at 53, 54 with the contacts 55 and 56. Pins 46, 46', or any other suitable guides, may support the walls of slots 57 and thus support the contacts 55 and 56. Stems 58, 59 of the main 5 valves are pivotally connected with any desirable play to opposite ends of a lever 60 whose middle point is pivotally connected through the rod 61 with the control valve 36.

One important difference from the Bird Patent 10 No. 933,952 referred to above, lies in the character and point of operation in the sequence of operation of the control valve used. In the present form the control valve operates upon the exhausts of the cylinders successively so as to permit 15 comparatively free exhaust and hence comparatively free operation of the one engine cylinder while the other engine cylinder is slowed up by restricting its exhaust and then reversing this condition to restrict the exhaust of the first- 20 mentioned cylinder while permitting comparatively free exhaust of the second cylinder, with corresponding operation of its engine.

The exhaust takes place from the respective engine cylinders 10 and 11 through the control 25 valve, passing through its cylindrical outer shell by ports 63 and 64 which register in different positions of the control valve with relatively free valve port 65 and restricted valve port 66 respectively, when this valve is in the position shown 30 in Figures 1 and 3 at the extreme right; with restricted valve port 67 and relatively free valve port 68, respectively, when the control valve is in its central position, as in Figures 4 and 6, and with relatively free valve port 69 and restricted 35 valve port 70, respectively, when the control valve is in its extreme left hand position.

In Figures 3, 4, 5 and 6 I have shown in a much 40 more diagrammatic form the various positions of the engine pistons, pilot valves, main valves and control valves in engines 10' and 11' to explain the operation of the engines. In these 45 figures the pilot valves are shown at 22², 23² controlling steam admission and exhaust to and from main valve pistons 28², 29². The slide valves 30² are thus shifted to provide inlet and exhaust from the engine cylinders 10, 11' having pistons 44', 45'. Steam passages are shown at 25', 27', 31², 32² and 33². Hand-operated cut off valves, one for each exhaust, are shown at 34².

50 The control valve 36' is shifted by rod 38' and the pilot valves are shifted by rods 39² controlled by levers 41', 42' set in operation by piston rods 43².

The levers 41', 42' are pivoted at 46² about pins 55 supported at 48'. These levers are swung by engagement of their forked ends 49' with pins 50', 51' carried by the piston rods. The noses 53', 54' of the lever engage with limiting walls 55', 56' to shift the pilot valves, the spacing between 60 these walls providing lost motion between these shifting movements.

The control valve 36' is substantially identical with that shown in Figure 1 and the various ports from it as well as into it have therefore been given the same reference characters, as in Figure 65 1, but with primes.

There is a slight difference at the back of the valve 36' as compared with valve 36. The back of valve 36' is wholly open and the rod 38' is attached to the walls of the valve, which walls serve as ears.

In both of the control valves, ports 71 have been shown as located in opposite sides of the valve spaced 90° with respect to the ports 65-70, 75 65'-70'. In connection with this, turning mech-

anism has been shown here (and also in Figure 1) at 72 operated through a handle 73, whereby the rod 38' can be turned a quarter turn with respect to the position of the lever 60, displacing the ports 65-70, 65'-70', and substituting in front of the ports 63 and 64, 63' and 64' these ports 71, with the result that exhaust through ports 63 and 64, 63' and 64' takes place freely whatever the longitudinal position of the control valve 36 or 36'. This permits both engines to operate 10 freely and independently.

Separate exhaust from the pilot valve cylinders is shown in Figure 1 through pipes 76, shown diagrammatically in the other figures at 76'.

The usual packing and sealing devices for the 15 several rods and heads are intended to be used as indicated. The lining for the control valve cylinder 35, Figure 1, permits greater accuracy in finishing the cylinder.

In operation, starting with the parts in the position shown in Figures 1 and 3: piston 44 or 44' is shown at an intermediate point in the engine cylinder 10 or 10' and has just moved there from the left-hand end in the illustration. This cylinder in advance of the piston (at the right of the 25 piston) has comparatively free exhaust through the ports 63 and 65, the control valve being at its extreme right-hand position and both ends of the lever 60 occupying their extreme right-hand positions.

The piston 45 or 45' is at its extreme left-hand position and movement to the right is restricted by the fact that exhaust from the right end of this cylinder through the passages 32, 33' is restricted because of the small size of the port 66. 35

Under these conditions the piston 45 or 45' moves but slowly to the right whereas the piston 44 or 44' completes its stroke at a much higher rate. With completion of the stroke of pistons 44 or 44' lever 41 or 41' is shifted with corresponding movement of the pilot valve controlling the corresponding cylinder. This throws the pilot valve to the left, allowing steam inlet to the right-hand end of the main valve for cylinder 10 or 10'. Meantime piston 45 or 45' has been slowly moving to the right. The parts thus come into the position seen in Figure 4 in which piston 44' is at the extreme right hand, the piston main valve for cylinder 10' has been thrown to the left carrying slide valve 30² to the left and piston 45' is at an intermediate point in its stroke which may or may not be the middle of the stroke as shown.

Shift of the main valve for cylinder 10 as in Figure 4 not only admits steam to the right hand end of the piston 44 or 44' but at the same time shifts the end 60' of the lever 60 through the movement of rod 58 or 58'.

The lever 60 shifts about the end 60² as a pivot with the result that the middle of the lever at 60 60³, is shifted to half the distance, rod 38 or 38' is moved to the left and the control valve 36 or 36' is drawn to the left to its middle position where port 67 or 67' now restricts exhaust from the cylinder 10 or 10'. 65

The same movement of the piston which brings port 67 into restricting position in front of port 63 brings port 68 in front of port 64 so that engine 10 or 10' can exhaust more freely, allowing piston 45 or 45' to move to the right. 70

The coincident shifts of piston, valves and lever which take place as piston 44 or 44' reaches the right hand end of its stroke are shown as having been accomplished in Figure 4.

With continuation of the movement of piston 75

45 or 45' to the right—permitted by the larger exhaust opening 68 or 68'—piston 45 or 45' comes to the right hand end of the cylinder 11 or 11' causing the pilot valve for cylinder 11 or 11' to shift to the left, which admits steam to the corresponding main valve at the right hand end in the figures, causing this piston valve to move to the left. Movement of this piston valve, through rod 59 or 59' shifts the end at 60² of the lever 10 to the left, causing a further movement of the control valve 36 or 36' to the left, to its extreme left hand position.

Meantime, the main piston 44 or 44' in cylinder 10' begins its movement to the left and the parts assume momentarily much the positions seen in Figure 5, where exhaust from cylinder 10 or 10' is comparatively free and exhaust from cylinder 11 or 11' is seriously restricted.

With movement of the piston 44 or 44' from the position of Figure 5 toward the left hand end of the cylinder and consequent shifting of the main valve pistons to the right, the end at 60² of the rod 60 is drawn to the right, the control valve is brought back to the middle of its stroke and piston 45 or 45' is started on its stroke to the left. This position is shown in Figure 6.

When the piston 45 or 45' completes its stroke to the left the pistons of the main valve are returned to the right hand position shown in Figures 1 and 3, the lever 60 is thrown to its position of Figures 1 and 3 and the control valve is thrown all the way to the right so that the parts again occupy the position at which the cycle started, as seen in Figures 1 and Figure 3.

When it is desired to operate one engine only the corresponding valve 34 or 34' may be closed wholly to shut off the exhaust from the corresponding engine cylinder.

It will be evident that a quarter turn of the control valve for the special ports and a selective use of the valves 34, 34' make it possible to run either engine alone on free exhaust or to run both engines at the same time on free exhaust. When it is desired to run one engine freely and independently, without running the other engine, the stoppage of the other engine can be effected alternatively by closing the main intake or shutting off the exhaust of the engine to be shut down before it reaches the port 71. The valves 34, 34', 34² afford convenient means for this purpose.

It will be evident that the circumferential shift of the control valve to present ports 65—70 or 65'—70' alternatively to ports 71 may be provided with a detent 71 which will engage from one part with the other in full stroke position to hold the parts reliably against accidental shifting to intermediate position.

In view of my invention and disclosure, variations and modifications to meet individual whim or particular need will doubtless become evident to others skilled in the art to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:

1. The method of operating two engines having separate cylinders, pistons, inlet and outlet passages and operating valves, and maintaining each at the average speed of the other, which consists in restricting the exhaust for the next stroke in each cylinder in agreement with the

movement of the piston in that cylinder and in relieving the restriction of the exhaust in accordance with the operation of the piston of the other cylinder during its intervening stroke, and so on.

2. The method of maintaining substantial synchronism between the operations of a pair of engines, each engine having its individual operating equipment, which consists in reversely adjusting the freedoms of exhaust of the respective engines in timing with the successive engine strokes and toward the completions thereof, each adjustment tending to lessen the speed of the engine in which the adjustment is made and to increase the speed of the other engine.

3. The method of maintaining substantial synchronism between the operations of a pair of engines, each engine having its individual operating equipment, including an exhaust and a valve adapted to determine the engine strokes, which consists in momentarily slowing down each engine at the completions of the strokes of its valve by throttling the engine exhaust.

4. The method of maintaining substantial synchronism between the operations of a pair of engines, each engine having its individual operating equipment, including an exhaust and a valve adapted to determine the engine strokes, which consists in additionally temporarily opening the exhaust of the one engine near the end of the stroke of the determining valve of the other engine in order to cause temporary relative increase of speed of the second engine with respect to the first.

5. The method of maintaining two engines in substantial step, each engine having its individual operating equipment, which consists in adjusting the exhausts of each near the end of the stroke of the other somewhat throttling the exhaust of the engine just completing the stroke and additionally opening the exhaust of the other.

6. The method of operating two steam engines in relative step, each engine having its individual operating equipment including pistons and exhaust ports, which consists in decreasing the speed of each engine as it completes its stroke by restricting its exhaust and concurrently increasing the speed of the other by relatively freeing its exhaust.

7. The method of maintaining two engines in substantial step which consists in regulating the exhaust of each according to the position of the piston in the other, reducing the speed of one while increasing the speed of the other, first upon one engine and then upon the other engine and so on.

8. A pair of engines having inlets, exhausts, operating valves, pilot valves and means for altering the resistance to exhaust at a point beyond the normal engine exhaust, and connections between a movable part of each engine and the controlling valve of the same engine, adapting the shifts of the respective valves to effect reverse changes in the exhaust pressures of one of the engines, each shift tending to increase the exhaust pressure of the engine making the shift and to decrease the exhaust pressure of the other engine.

9. A pair of engines having inlet and exhaust ports and supplemental adjustable exhaust ports and operating valves, pilot valves and connections between a movable part of each engine and the controlling valve of the same engine, adapting the shifts of the respective valves to

- reversely adjust the exhaust ports, each shift tending to somewhat close the exhaust port of the engine having the valve making the adjustment, and to additionally open the exhaust port 5 of the other engine.
10. In a multiple cylinder unit, a pair of cylinders, pistons and piston rods for the respective cylinders, walls forming inlet and exhaust passages to and from the said cylinders, a main valve for each of said cylinders, a pilot valve and fluid connections for each main valve, an exhaust control valve common to the two cylinders, connections between the main valve operating mechanisms and the control valve and connections between the respective piston rods and the pilot valves, whereby the operation of the main valve by the pilot valve for each stroke of one cylinder shifts the control valve part of its stroke in one direction and operation of the main valve by the pilot valve of the other cylinder by movement of the piston rod of said cylinder completes movement of the control valve in said direction.
11. Multiple engine cylinders, pistons and piston rods for the cylinders, main valves and walls forming inlet and exhaust passages for the cylinders, pilot valves for the main valves, a control valve having ports restricting the discharge from one cylinder and providing fuller discharge in the other cylinder with different positions of the control valve, interconnection between the main valves and control valve whereby the control valve is moved due to shift of the main valves and means for operating the pilot valves by reason of movement of the pistons, to shift the control valve position after each operation of a piston in one cylinder a direction such that the control valve restricts subsequent exhaust from that cylinder and facilitates exhaust from the other cylinder.
12. A pair of separate engine cylinders, pistons and piston rods for the cylinders, main valves and pilot valves controlling inlet and discharge of steam to and from the respective cylinders, connections between parts movable with the pistons and the pilot valves whereby the pilot valves are controlled in position by the movement of the pistons, exhaust control mechanism for restricting or facilitating exhaust from the several engines alternately and connections between the main valves of the cylinders and said exhaust control mechanism whereby the exhaust control mechanism restricts exhaust from each cylinder after it has made its stroke 55 until the opposite cylinder has moved and substantially permits enlarged exhaust from said cylinder.
13. In a multiple engine, a pair of engine cylinders, pistons and piston rods therefor, main valves controlling inlet and exhaust passages to and from said cylinders, pilot valves for said main valves, a valve for additional control of the exhaust from said cylinders, having ports providing, in each of its positions, for relatively free exhaust from one of said cylinders and relative restriction of exhaust from the other of said cylinders, alternating the control valve's successive positions as to the exhaust from which cylinder is restricted, lever means movable at its ends with the main valves and movable at an intermediate point with the control valve whereby the position of the control valve is determined by the positions of the main valves, to successively vary the position of the control valve 75 and alternately restrict exhaust from the two cylinders and connections from the respective piston rods to the pilot valves whereby the pilot valves are shifted with movement of the piston rods for the same engine cylinder.
14. In a multiple engine, a pair of cylinders, pistons and piston rods therefor, main valves controlling inlet and exhaust passages to and from said cylinders, pilot valves for said main valves, a control valve for the exhaust from said cylinders having ports providing in each of its positions for relatively free exhaust from one of said cylinders and relative restriction of exhaust from the other of said cylinders, alternating its successive positions as to the cylinder 15 from which exhaust is restricted, lever means movable at its ends with the main valves and at an intermediate point with the control valve whereby the position of the control valve is determined by the positions of the main valves to 20 successively vary the position of the control valve and alternately restrict exhaust from the two cylinders, connections from the piston rods to the pilot valves whereby the pilot valves and by them the main valves are shifted with movement of the piston rods of the same engine and separate valve means for closing off the exhaust of each of the cylinders at will.
15. In a multiple engine, a pair of cylinders, pistons and piston rods therefor, main valves 30 for inlet and exhaust passages to and from said cylinders, pilot valves for said main valves, a control valve for the exhaust from said cylinders having ports providing in each of its positions for relatively free exhaust from one of 35 said cylinders and relative restriction of exhaust from the other of said cylinders, alternating its successive positions as to the cylinder from which exhaust is restricted, lever means movable at its ends with the main valves and 40 at an intermediate point with the control valve, whereby the position of the control valve is determined by the positions of the main valves to successively vary the position of the control valve and alternately restrict exhaust from the 45 two cylinders, connections from the piston rods to the pilot valves whereby the pilot valves and by them the main valves are shifted with movement of the piston rods of the same engine, means for separately shifting the control valve 50 and additional ports in the control valve whereby both cylinders may exhaust freely through the control valve in all positions of the control valve.
16. In a multiple engine, a pair of cylinders, 55 pistons and piston rods therefor, main valves controlling inlet and exhaust passages to and from said cylinders, pilot valves for said main valves, a control valve for the exhaust from said cylinders having ports providing in each of its 60 positions for relatively free exhaust from one of said cylinders and relative restriction of exhaust from the other of said cylinders, alternating its successive positions as to the cylinder from which exhaust is restricted, lever means 65 movable at its ends with the main valves and at an intermediate point with the control valve, whereby the position of the control valve is determined by the positions of the main valves to successively vary the position of the control valve 70 and alternately restrict exhaust from the two cylinders, connections from the piston rods to the pilot valves whereby the pilot valves and by them the main valves are shifted with movement of the piston rods of the same engine, 75

means for separately shifting the control valve, additional ports in the control valve whereby both cylinders may exhaust freely through the control valve in all positions of the control valve, and separate valve means for closing off the exhaust of each of the cylinders at will.

17. A pair of engines having inlets, exhausts, operating valves and means for altering the resistance to exhaust at a point beyond the normal engine exhaust and connections between the

valves adapting the shifts of the respective valves to effect reverse changes in the exhaust pressures in one of the engines, each shift tending to increase the exhaust pressure of the engine making the shift and to decrease the exhaust pressure of the other engine, in combination with means for selectively eliminating the alteration of resistance to exhaust at the point beyond the normal engine exhaust.

WARREN P. VALENTINE. 10
